UNITED STATES PATENT OFFICE.

PERCY H. THOMAS, OF UPPER MONTCLAIR, NEW JERSEY, ASSIGNOR TO COOPER HEWITT ELECTRIC CO., OF HOBOKEN, NEW JERSEY, A CORPORATION OF NEW JERSEY.

MERCURY-VAPOR APPARATUS.

1,110,603.

Specification of Letters Patent.

Patented Sept. 15, 1914.

Application filed February 3, 1913. Serial No. 745,787.

To all whom it may concern:

Be it known that I, PERCY H. THOMAS, a citizen of the United States, and resident of Upper Montclair, county of Essex, State of New Jersey, have invented certain new and useful Improvements in Mercury-Vapor Apparatus, of which the following is a specification.

My invention relates to mercury vapor rectifiers and more particularly to certain methods of construction and specific features affecting the operation of such devices as will be seen in the embodiments shown herein.

15 My apparatus is especially suited for practical use to give continuous and reliable service even with very heavy output or for translating devices requiring high voltages. I have embodied my general features of design as well as a number of novel details in a single device as a matter of convenience, but I wish it understood that the several features may be utilized separately where desirable.

25 The present rectifier is shown in Figures 1, 2, 3 and 4, where Fig. 1 is a half vertical section, Fig. 2 a half horizontal section on the line A—B, Fig. 3 shows an enlarged anode and Fig. 4 shows a tight bushing for permitting the entrance and exit of a cooling pipe. Fig. 5 shows suitable circuits for operating the present rectifier from a three phase system.

35 In the first figure, 1 represents my rectifier, 2 is the main shell of the container which may be of steel, iron, nickel, copper or brass, or some other material which is a conductor of electricity and can be suitably formed.

40 3 is the cap or dome of the container, preferably made in one piece and may be of porcelain or earthenware or glass or other suitable material; this cap may, however, be made of conducting material if the various 45 electrodes, cooling pipes and similar parts are insulated therefrom. This part is made dome shaped to help support the pressure of the atmosphere. To make this container perfectly gas tight it is, of course, necessary that the main cup, 2, be of impervious material and in one piece or that the joints be compressed or welded or otherwise closed

tight. Similarly with the cap 3. To cover the joint between the cap and the cup I may weld or otherwise tightly secure a thin flexible sheet of metal, 4, for example steel, to the flange, 5, of the cup 2. This sheet of metal, 4, may be formed to have an annular recess adapted to inclose the flange, 6, of the cap 3. The horizontal portions of this thin metal annulus may then be clamped to the flange, 6, and mercury introduced at 7, thus giving a mercury sealed joint and preventing the mercury from being spilled and also protecting the mercury.

65 The method of sealing the leading in conductors of the anodes, 8, will be described in connection with Fig. 3 and the entrance bushings, 9, for permitting the entrance of the cooling pipe, 10, will be described in connection with Fig. 4. The connection for receiving the rectified current may be welded or otherwise secured to the outside of the cup, 2, as shown at 11 so that no opening in the container is required for connection to 70 the cathode.

75 The anodes, 8, are placed symmetrically around the outer portion of the exhausted space, each being supported by and having its lead pass through the container cap 3. 80 The anodes are hollow and contain a vaporizable material such as water or mercury and the interior space is connected with a coil of pipe, 12, outside of and above the cap and a return connection is provided at 85 13. The cooling tubes, 12, are carried in a block, 52, which may be screwed on the top of the sleeve 29.

90 A flange, 14, shown also in Fig. 2 supported by the cap, 3, surrounds each anode leaving an opening at the bottom and an opening toward one of the other anodes. The cooling coil, 12, is supported on the rest, 15, suitably formed in the cap 3. This rest, 15, forms a pocket containing the lead 95 of the anode, 8, and serves to contain mercury, 16, for a seal for this lead.

98 As a means of disposing of a portion of the heat liberated in the container, I utilize the cooling coil or the pipe, 10. This coil 100 of pipe is carried upon a ring, 17, which may be of porcelain, earthenware, fused quartz, soapstone or other suitable insulating material. This ring, 17, serves both as

an insulating support for the coil 10 and to confine the point at which current enters the cathode to the central portion of the container. I provide a recess, 18, in the ring 17 to prevent the formation of a continuous stream or surface of mercury from the scum collecting thereon between the coil, 10, and the mercury, 19, which constitutes the vaporizable cathode. I also provide a passageway, 20, for maintaining a uniform level in the mercury inside and outside of the ring, 17. The top of the coil, 10, is guided and steadied by the cap, 3, which is suitably shaped for this purpose.

15 The arrangement of the pipes, 10, is such that the openings between the pipes in one row are covered by the pipes themselves in another row, the object being to require all the mercury vapor or current of electricity 20 passing through the coil to follow a devious and indirect path. The plate, 21, which may be an annulus or which may be of separate pieces is placed upon the top of the mercury outside of the ring, 17, to protect the anodes, 8, both from mercury and from electric effects.

25 Fig. 2 shows in plan most of the several parts already described and needs no further explanation.

30 The terminals of the coil, 10, are carried through the wall of the cup, 2, through the bushings, 9, 9, and insulating joints, 23, 23, are introduced outside of the container to keep the coil, 10, out of contact with external 35 conductors. These insulating joints include external insulating sleeves, 24, and internal insulating sleeves, 25. At 26 I have shown a connection for exhausting the gases from the rectifier which may be welded or otherwise tightly secured to the wall of the cup 2.

40 In Fig. 3, 8 is a main anode, 27 is a portion of the cap of the container, 18 the return tube from the cooling coil 12, and 28 is the lead and vapor tube connecting the 45 pipe, 12, with the inside of the anode, 8.

The tube, 28, is brazed or welded to the sleeve, 29, which, as well as the tube 28, may be of steel, so as to be air tight.

50 30 and 31 are nuts threaded on to the sleeve, 29, for the sake of clamping the rim, 27.

55 32 is a washer under the nut 31, and 33 is a diaphragm serving to inclose the mercury, 16, shown in Fig. 1.

60 34 is a cap of graphite, of steel or other material, fitting closely against the top of the anode, 8, and against the under surface of the rim, 27, to protect the upper portion of the anode, 8, and its lead. I have shown 65 the level of the mercury or other vaporizable material just within the anode, 8, at the point, 35. I have shown in Fig. 1 the joint between the sleeve, 29, and the rim, 27, is sealed by mercury, 16. A passageway, 36, is provided to permit the entrance of the seal-

ing mercury to a hollow annulus, 37, in the nut, 31, for the sake of sealing the thread joint at this point.

Fig. 4 shows the insulating bushing, 9, in detail.

70 38 is a metal sleeve welded or otherwise secured to the pipe, 10, and 39 is a portion of the shell of the cup, 2. The nuts 40 and 41 which are threaded on the sleeve, 38, serve to clamp the rim, 39. The ring 42 and the collar, 43, are of porcelain or other insulating material and serve to insulate the sleeve, 38, from the rim, 39.

75 44, 45, 46 and 47 are various washers located as shown. The joints are sealed by 80 mercury in the two annular spaces 48 and 49 which are filled by the passageways 50. When the mercury is in place a cap bolt, 51, may be placed in the outlet, of the passageways, 50, to confine the mercury.

85 The operation of this rectifier is as follows. The flow of current between the anodes and the cathode occurs by way of the central space in the container through the coil of the pipe, 10, to the side openings in 90 the flanges, 14, to the anodes, 8. The "negative flame," so-called, discharges directly upward into the dome of the cap, 3, and the anodes are separated therefrom by the coil of pipe, 10, the openings in any one row 95 of pipes being covered by the pipes of at least one other row. This is a very effective arrangement since the anodes are protected from all sorts of possible deteriorating influences, whether these be the effect of 100 the negative flame (sometimes called emanations from the cathode), the spattering of mercury, the dropping of mercury or the effect of electric charges, of a positive character which may be drawn toward an 105 anode; from the latter, since I connect the coil pipe, 10, to a source of potential which is intermediate between the potential of the cathode and that of the non-operating anodes. This I accomplish as shown in Fig. 110 5 or as provided in my application Serial Number 664,169, filed December 6th, 1911.

In case it is desired to utilize separate electrodes as means for protecting anodes of various polarities, the several rows of 115 pipe shown in Fig. 1 may be made separate or be insulated from one another suitably for connecting to a supply of electrical energy in the manner shown in my last mentioned co-pending application. In Fig. 120 1 these coils are shown as insulated by a ring 17 in the manner shown in my last mentioned co-pending application.

125 My rectifier is unusually well adapted to the disposal of the heat liberated by the flow of current and to meeting the other unfavorable effects thereof. Not only does the container, and especially the metal part thereof, expose a large surface for the disposal of heat, which surface may be im- 130

mersed in a cooling liquid or otherwise artificially cooled, but I provide in the coils, 10, a very powerful means for cooling the vapor, through the circulating fluid which 5 may be passed through this pipe. By causing the entering water to traverse first the outer row of pipes, I apply the cooling means at its most effective temperature to the remnants of the vapor which has not 10 been condensed by the inner rows of pipes. The pipes, 10, not only thus have a very intimate contact with the vapor to be condensed but serve to a certain extent to limit, by throttling, the amount of vapor 15 escaping into the outer sections of the vacuum space, where the anodes are located, so that the cooling provided by the walls of the cup, 2, will be able to maintain a very perfect vacuum around the 20 anodes. This is well known to be one of the most effective means for preventing the difficulty known as short circuiting. Thus, in effect, the coils of the pipe, 10, separate the central portion of the rectifier where 25 the negative flame and high pressure mercury vapor are found, from the outer region which may be maintained at a very much lower temperature. This separation is both 30 mechanical and electrical, at least as far as the protection of anodes from deteriorating electric effects is concerned. The location of the exhaust outlet, 26, in the anode region is favorable, since at this point the amount of mercury vapor is relatively small, since 35 it is the natural collecting place for non-condensable gases, and since this is the region in which purity is more particularly required. It is clear that should any mercury have a tendency to drop or splash from 40 the pipes, 10, this could not reach the anodes in view of the flanges, 14, and yet the passages for the flow of current from cathode to anode are wide and free as far as their 45 sectional area goes, though, of course, they are very indirect.

In many places, I prefer to use mercury as the cooling material in the hollow anodes, 8, since it is desirable that this anode, during operation, be neither very cold nor extremely hot. Obviously, if atmospheric pressure is present in the tubes 12, there will be initially little or no vaporization of the mercury within the anode 8 and, as little cooling is taking place at this time, the 50 temperature of the anode will rise rapidly. When, however, the boiling point of mercury at atmospheric pressure, which is in the neighborhood of three or four hundred degrees centigrade, is reached, large volumes 55 of mercury vapor will be produced which will pass up the tube, 28, and be condensed in the coil of the pipe, 12, and then returned to the interior of the anode through the tube, 13. The effectiveness of the tubes, 12, may be 60 greatly increased by the use of air blast or

cooling liquid. By changing the liquid in the anode, 8, or the pressure in the tube, 12, the point at which vaporization of the inside liquid occurs and the temperature of the anode can be thus controlled. 70

To maintain atmospheric pressure in the tube, 12, I may insert a porous plug, 75, as shown. Another advantage of the use of mercury within the anode 8 is that the condensation in the tube, 12, tends to take 75 place at a relatively very high temperature such as the three or four hundred degrees centigrade already spoken of, which will greatly assist the dispersal of heat from the tubes, 12. 80

The plate, 21, serves to protect the anodes, 8, electrically and mechanically from the presence of the mercury, 19. 85

In Fig. 5, 53, 54 and 55 are three delta connected transformer primaries; 56, 57 and 58 are respectively the corresponding secondaries for these primaries. These secondaries are connected to the six main anodes in the same order around the container in which the sequence of the phases 90 flow. In other words, the two anodes adjacent to any given anode are the anodes nearest in potential thereto. By this means it is possible to keep at its minimum the potential between an adjacent pair of 95 main anodes. The central points of the secondaries 56, 57 and 58 are connected by the conductor, 59, to the negative side of a work circuit, 60, while the cathode, 19, of the device is connected through the choke 100 coil, 65, to the opposite side of the work circuit. I provide a switch, 66, whereby, if desired, the coil, 65, may be short circuited. 105

This coil may act either to smooth out the waves or to keep alive the rectifier as may be required. In case no other keeping alive means are provided, this coil, 65, will maintain continuity of current in the cathode, even in the case when the counter electromotive force of the motor, 67, in the work circuit is greater than the minimum points of the effective supply voltage. The cooling coil, 10, is connected through the inductance, 64, and resistance, 63, to the contact arm, 62, which may be connected to various points on the potentiometer shown at 61. The effect of this potentiometer connection is to permit any given condition of potential in the negative direction between 110 the cathode, 19, and the cooling coil, 10. 115

I may provide, though this is not necessary, a keeping alive primary whose secondary is shown at 68 connected through the inductances 69 and 70 to two supplementary anodes 72 and 73. An intermediate point of the secondary, 68, is connected through the inductance, 71, to the main cathode. The inductance, 63, and the inductance, 64, serve to limit the amount 120 125 130

of leakage current taken up by the cooling coil, 10, operating as a protecting negative electrode, and also preventing an accidental disturbance therein from establishing continuous operation upon this coil as a cathode.

If desired, I may dispense with this use of the cooling coil by opening the switch, 74. It should be understood that this rectifier may be used with other types of circuits, for example with any of the appropriate circuits in my co-pending application Serial Number 745,786, filed February 3rd, 1913.

It will be understood that it may be desirable to operate this rectifier in practical service with a continuously operating vacuum pump to preserve the highest degree of vacuum and reliability. It will be further understood that the substance of the principles and features shown in the present rectifier may be attained by the use of various mechanical and electrical equivalents therein, which it is not necessary here to illustrate. I wish to include all such modifications in my invention. While I have described the mercury, 19, as the material of the cathode, I do not wish to limit my invention to this particular material for other materials will serve as well under appropriate conditions. Furthermore many of the combinations and structures of the present apparatus may be utilized in vapor apparatus not intended for rectification and these also are included in the scope of the present invention. Where relatively low voltages for small currents are to be utilized, it may not be necessary to use all of the features herein shown. For example, the flanges, 14, may be omitted or fewer coils of pipe utilized or the plates, 21, dispensed with, or the cathode material, 19, may be included in an insulating cup not being in electrical connection with the conducting portion of the container.

Any suitable means may be utilized for starting this rectifier, either high potential, or one or more auxiliary electrodes, which may be introduced through the cap, 3, in the central portion, if desired, or may be located in the portion of the container inclosing the main anodes. It will frequently be desirable to supply means for exciting the cathode continuously or intermittently as by passing direct current continuously therethrough in the positive direction. All these conditions, as well as various means for improving the vacuum by chemical absorption or by the seclusion of residual gases in separate chambers may be combined in the present apparatus without departing from this invention.

I claim as my invention:

65 1. A mercury vapor rectifier comprising

an exhausted container, including a hollow lower portion, and an insulating dome shaped upper portion, an active cathode in the central portion of said container, a plurality of main anodes in the outer portion of said container and an interposed coil of cooling tubes between said cathode and said anodes. 70

2. A mercury vapor rectifier comprising an exhausted container, including a hollow lower portion, and an insulating dome shaped upper portion, an active cathode in the central portion of said container, a plurality of main anodes in the outer portion of said container and an interposed coil of cooling tubes between said cathode and said anodes, said cooling coil being of conducting material and being maintained at a potential negative with respect to that of the cathode. 75

3. A mercury vapor rectifier comprising an exhausted container, including a hollow lower portion, and an insulating dome shaped upper portion, an active cathode in the central portion of said container, a plurality of main anodes in the outer portion of said container and an interposed coil of cooling tubes between said cathode and said anodes, and means for maintaining said coil at a potential below that of the cathode, said means consisting of a resistance coil with taps shunted on the receiving circuit of said rectifier and a connection from said shunt to said cooling coil. 80

4. A mercury vapor rectifier comprising a container composed principally of conducting material, a plurality of anodes therein, a cathode therein and a cooling coil of conducting material electrically insulated therefrom. 100

5. A mercury vapor rectifier comprising an exhausted container having a series of anodes therein in combination with an insulating flange with a wide opening therein surrounding each anode, the openings in the several chambers formed by the flange being faced in the same direction along a line connecting the anodes. 110

6. A mercury vapor rectifier comprising an exhausted container having a series of anodes therein in connection with a flange with a wide opening therein surrounding each anode, the openings in the several chambers formed by the flange being faced in the same direction along a line connecting the anodes. 115

7. A mercury vapor rectifier comprising a container made up of a cup shaped hollow lower portion and a dome shaped insulating upper portion, mercury in the bottom of said cup shaped portion constituting a cathode, an insulating ring inclosing a central portion of said mercury electrode, a coil of conducting cooling pipe resting on said insulating ring and extending upward into 120

125

130

- close proximity to said dome shaped top, a series of anodes arranged in a circle outside said cooling pipe, said anodes being carried by said top, partly closed circular flanges surrounding said anode, opening circumferentially, external cooling condensing means connected with the interior of said anodes and means for maintaining the potential of said cooling coils below that of 10 said cathode.
8. In an exhausted vapor rectifier, means for sealing the joint between two parts therefor, one of said parts being of metal, said means consisting of a flexible thin sheet of metal welded near one edge to the said 15 metal portion of the container on the pressure surface exposed to the other part and means for clamping the other edges of said thin metal piece to the last named portion of the container and mercury acting as a 20 seal disposed in the pocket thus formed.
- Signed at New York in the county of New York and State of New York this 1st day of February, A. D. 1913.
